UNITED STATES PATENT OFFICE

2,314,292

ELECTRIC ARC-EXTINGUISHING APPARATUS

Oliver C. Traver, Drexel Hill, Pa., assignor to General Electric Company, a corporation of New York

Application October 2, 1940, Serial No. 359,371

12 Claims. (CL 200—147)

My invention relates to electric arc-extinguishing apparatus having particular application to electric circuit-interrupting devices, such as circuit breakers, lightning arresters, and the like, of the magnetic blow-out type employing an arc chute into which the arc is directed and extinguished.

The use of insulating arc chutes in connection with interrupting electric currents is a well-known and accepted practice. In general, the arc is forced into the arc chute by suitable means, such as a magnetic blow-out coil and is stretched and elongated, thereby increasing the arc resistance until the arc is extinguished. In the case of heavy currents, however, this method alone may be insufficient for the arc may be blown entirely through the chute without being extinguished.

In a more effective form of arc chute it has been proposed appreciably to elongate the arc path within the chute by means of spaced interleaving ribs or fins extending from the opposite walls of the chute so as to form a restricted tortuous passage, generally of zigzag form, for the arc as it proceeds through the chute. The closely confining walls of this passage also extract heat from the arc stream, thereby increasing the resistance of the arc to a further extent and aiding in the interruption thereof.

It is an object of my invention to provide a new and improved arc-extinguishing apparatus of the aforesaid type in which the configuration of the arc passageway is such as to increase the interrupting ability of the apparatus.

It is another object of my invention to provide a new and improved arc-extinguishing apparatus including a plurality of arc chutes serially arranged with respect to said arc.

Still another object of my invention is to provide a new and improved circuit-interrupting device comprising a plurality of arc chutes and means for forcing the arc drawn into said chutes to extinguish the same rapidly.

Still another object of my invention is to provide a new and improved electric circuit-interrupting device including a plurality of arc chutes and fluid-pressure generating means to force said arc into said arc chutes to extinguish the same rapidly.

Further objects and advantages of my invention will become apparent as the following description proceeds and the features of novelty which characterize my invention will be pointed out with particularity in the claims annexed to and forming a part of this specification.

In circuit-interrupting devices of the prior art, arc chutes of the general type comprised interleaving fins which were evenly spaced and made as plates or ribs of uniform thickness projecting perpendicularly from the walls of the arc chute. Such a device is shown, for example, United States Letters Patent No. 2,293,513, Linde, granted August 18, 1942, and assigned to the same assignee as the present application. It is recognized by those skilled in the art that the circuit-interrupting ability of an arc-extinguishing device of the type referred to above is increased when the heat transfer between the arc and the arc chute is increased and arrangements have been proposed for obtaining more extensive heat transfer between the arc and the arc chute. Such an arrangement is disclosed and claimed in United States Letters Patent 2,306,204, Boehne, granted December 22, 1942, and assigned to the same assignee as the present application. My invention is an improvement on the above-mentioned Boehne patent in that a more extensive heat transfer between the arc and the arc chute is promoted by the particular arrangement of the arc chute, thereby greatly increasing the interrupting capacity of the arc-extinguishing apparatus.

Since arc chutes of the interleaving type may be constructed of fragile material, such as of a ceramic nature, the probability of fracture would be relatively great, which might make the circuit-interrupting device practically useless in so far as its intended purpose is concerned. I propose to provide a circuit-interrupting device in which the probability of rendering the circuit-interrupting device useless by virtue of fracture of the fragile arc chute is greatly decreased.

For a better understanding of my invention, reference may be had to the accompanying drawing in which Fig. 1 is a schematic diagram partly in section of an electric circuit-interrupting device embodying my invention, Figs. 2 and 3 are complete sectional views taken, respectively on lines 2—2 and 3—3 of Fig. 1, assuming Fig. 1 to be a complete view although actually shown in section in the interest of clearness, Fig. 4 is similarly a view only of the interleaving arc chute taken from line 4—4 of Fig. 1, and Figs. 5 and 6 are sectional views taken respectively on lines 5—5 and 6—6 of Fig. 1 and, except for being sectional views, are similar to Fig. 4.

Referring now to the drawing, I have illustrated my invention specifically as applied to an air circuit breaker of the magnetic blow-out type but it will be understood by those skilled in the

art that my invention is equally applicable to lighting arresters, and fluids other than air might also be used successfully. The circuit-interrupting device of Fig. 1 is illustrated as comprising a pair of relatively movable contacts 11 and 12 arranged in a suitable arc-extinguishing structure generally indicated at 13 and supported on suitable insulating means 14 and 15, which means might, as illustrated, also serve to house the electrical connections leading from contacts 11 and 12 to the associated power circuit, not shown. This circuit may preferably be connected to stationary contact 11 through a spirally arranged blow-out coil 16 which includes a magnetic core 17. For electrical and mechanical reasons, blow-out coil 16 is illustrated as comprising two spiral portions 16' and 16'' separated by an insulating barrier 18 (Figs. 2 and 3), whereby both the terminals thereof are on the outside of the spiral. For the purpose of simplifying the disclosure, the insulation around blow-out coil 16 has not been shown but it will, of course, be understood by those skilled in the art that such insulation will be provided and, furthermore, the cross section of this blow-out coil will be determined by the amount of current to be carried thereby.

Movable contact 12 may be connected to the other terminal of the circuit-interrupting device in any well-known manner. Also, any suitable means, such as the solenoid shown, may be provided for operating contact 12, and, consequently, producing relative movement between contacts 11 and 12. In the event that the arc-extinguishing device of my invention is to be used as a lightning arrester, it will be understood that contacts 11 and 12 will be permanently separated to form a gap across which an arc will be formed upon the occurrence of a lightning surge and, consequently, means for producing relative movement between contacts 11 and 12 will not be required.

The arc-extinguishing structure, generally indicated at 13, comprises a pair of disk-shaped plates 19 and 20, Figs. 2 and 3, mounted parallel with one another and between which are supported the arc chutes to be described herein-after. These plates engage respectively the ends of magnetic core 17. A plurality of arc chutes 21 are supported between disk-shaped plates 19 and 20 and, as illustrated in Fig. 1, are circumferentially arranged around blow-out coil 16. Preferably, suitable insulating members 22, Figs. 2 and 3, separate disk-shaped plates 19 and 20 from the arc chutes 21 which they support. The arc chutes 21 are spaced from one another by means of triangular inserts 23, 24, 25, and 26, which are formed of a suitable insulating material with the inner edges thereof, 23', 24', 25', and 26', respectively, adjacent the arc drawn in arc-extinguishing structure 13 being formed of an insulating material of a type preferably composed of a gas-evolving or gas-emitting substance, such as horn fiber or the like, so as to produce an arc-extinguishing gas when subjected to the heat and other action of the arc. These arc chutes 21 are preferably constructed of a ceramic material and, as illustrated, may be supported so as to form a strong unitary structure by being keyed to triangular inserts 23, 24, 25, and 26, as indicated at 27 so as to provide a cylindrical structure with the arc chutes 21 arranged around the circumference thereof suitably spaced from one another by virtue of the triangular inserts 23 to 26. It will be obvious

that, by this arrangement, any one of the fragile arc chutes 21 of ceramic material might be replaced in the event that it should break, thereby considerably reducing the cost of repair. Furthermore, the fact that one of the arc chutes 21 was broken would not render the circuit-interrupting device useless as the remaining arc chutes would interrupt the arc with somewhat decreased efficiency.

10 I have illustrated the arc chutes 21 as all identical in structure but the inserts 23, 24, 25, and 26 are different in that the inserts designated by the higher numerals are larger and extend farther into the cylindrical arc-extinguishing structure 13 so that the arc is forced into more intimate contact with the gas-evolving portions 23', 24', 25', and 26' thereof as it is extended in length. Incidentally, these gas-evolving portions 23', 24', 25', and 26' should preferably be replaceable as will be understood by those skilled in the art.

15 A suitable arc runner 28 is circumferentially arranged within the arc-extinguishing structure 13 in such a manner that, as the arc travels along the arc runner by virtue of the magnetic forces produced by blow-out coil 16, it is forced into more and more intimate contact with the gas-evolving material 23', 24', 25', and 26', respectively.

20 In order that a suitable fluid blast may be provided to aid blow-out coil 16 in forcing the arc into arc chutes 21, the walls of the cylindrical arc-extinguishing structure between arc runner 28 and arc chutes 21 are each preferably covered with a layer of gas-evolving insulating material 29. This gas-evolving material is illustrated in Fig. 1 as being suitably keyed at 30 at one end thereof to one of the arc chutes 21 while, at the other end thereof, it is keyed at 31 to triangular insert 23. It will be obvious to those skilled in the art that, instead of keying arrangements 27, 30, and 31, illustrated in Fig. 1, any other fastening means may be utilized which provide a structure sufficiently strong to withstand the forces involved. It will be observed that the arc chutes 21, inserts 23, 24, 25, and 26, and gas-evolving material 29 are keyed together as a unitary structure which is further supported by plates 19 and 20.

25 30 The two layers of gas-emitting insulating material 29 are separated sufficiently to define a space 32 therebetween, Figs. 2 and 3, for the arc, which space leads to the entrances 33, Figs. 1 and 6, of arc chutes 21. This space will be proportioned so as not to impede the arc in its movement into arc chutes 21 and yet so that sufficient gas is evolved from the gas-emitting insulating material 29 so that a blast of fluid under pressure aids the blow-out coil 16 in forcing the arc into arc chutes 21.

35 40 In order to decrease the possibility of restriking of the arc, I may provide means for displacing the ionized air adjacent contacts 11 and 12 during a circuit-interrupting operation and replacing it with un-ionized air. In the drawing, I have illustrated an arcuate recess 34 cut in each of the gas-evolving insulating members 29 to accommodate a movable vane 35 which is integrally connected with the means for operating movable contact 12. The vane 35 and movable contact 12 are shown dotted in Fig. 1 in the positions which they assume when the circuit breaker is open.

45 50 Each of the arc chutes 21 is arcuate in shape and comprises a pair of plates preferably com-

posed of arc-resisting material, such as, for example, an asbestos compound or a suitable arc-resisting ceramic material. Each wall of the chute is provided with a plurality of radially extending rib-like fins or ridges 36 and 37, respectively, and those ridges 36 and 37 are preferably integral with the side walls of the arc chutes 21. As best shown in Figs. 4 and 5, these ridges or fins are saw-toothed in shape and the projection of the fin is a maximum at the outer circumference of the circuit breaker structure 13 and dwindles down to zero at the inner edge of arc chute 21. The ridges of the two parallel plates comprising arc chutes 21 are so arranged with respect to each other as to be interleaved when the plates are in position, as shown in Fig. 2, so as to form a zigzag passage 33", as shown in Fig. 4. This passage increases in length with respect to the arc as the arc is driven farther and farther into the chute, the chute being constructed so that, at the entrance thereof, the passage 33, see Fig. 6, is relatively short, and which increases in length while traversing the chute. In Fig. 5, the passage 33' is shown as longer than the passage 33 of Fig. 6 but shorter than the passage 33" of Fig. 4. Furthermore, in accordance with my invention, the interleaving barriers or ridges 36 and 37 are gradually and progressively thickened from the inner edge of arc chute 21 to the outer edge thereof to effect a gradual squeezing of the arc along its whole length, thereby forcing the arc into more intimate contact with the arc chute, consequently increasing the heat transfer and aiding the interruption thereof. The arrangement is preferably such that the product of the length and the width of the arc path at the entrance of the arc chute is substantially equal to this product at the exhaust extremity of the arc chute.

The operation of my improved circuit-interrupting device will now be described with reference to Fig. 1. When relative movement between contacts 11 and 12 is produced, an arc is drawn therebetween. Electromagnetic blow-out coil 18 produces magnetic forces which quickly propel the arc along arc runner 28 and press it radially outward against the gas-emitting surfaces 23', 24', 25' and 26' and into arc chutes 21, greatly increasing its length and, consequently, also the arc resistance. The arc also coming in contact with gas-emitting material 29 causes gas to be evolved which aids the blow-out coil 18 in forcing the arc into the entrance passage 33, Fig. 6, of arc chutes 21. The arc also coming into intimate contact with the portions 23', 24', 25', and 26' formed of gas-evolving material produces a fluid under relatively high pressure which exhausts through the arc chutes 21 as a fluid blast forcing the arc with it. As the arc moves through the arc chutes 21, which are serially arranged with respect to the arc, the arc path continuously lengthens in view of the radially extending ribs or fins 36 and 37, providing a zigzag path transverse to the normal direction of arc expansion. Since the ribs 36 and 37 are gradually thickened toward the outer circumference of the arcuate-shaped arc chutes 21, the cross section of the arc path is gradually decreased and the arc is squeezed into more and more intimate contact with the arc chutes so as to be cooled and, consequently, extinguished in a very short space of time.

Although my invention also inherently embodies the unbalanced magnetic interaction of the magnetic forces on the arc so as to force the

arc against the portions of the arc chute, this feature is broadly claimed in the above-mentioned Boehne patent.

It should be understood that my invention is not limited to the specific construction and arrangement herein illustrated and that changes and modifications may occur to those skilled in the art without departing from the spirit and scope of my invention. I, therefore, aim in the appended claims to cover all such changes and modifications.

What I claim as new and desire to secure by Letters Patent of the United States is:

1. In an electric arc-extinguishing apparatus comprising an insulating arc chute into which the arc to be interrupted is directed having side walls disposed in closely spaced parallel relationship so as to form a narrow arc space therebetween, said walls on the sides facing each other having thereon in projecting relation interleaving ridges extending substantially transversely of the path of said arc, the ridges of one wall being spaced with respect to the interleaving ridges of said other wall and said ridges being so shaped and disposed as to provide for the arc a continuously lengthening path between said side walls which is zigzag transversely to the normal direction of arc expansion, said ridges being progressively thickened in the direction of arc expansion to effect a gradual squeezing of the arc along its whole length to force it into more intimate contact with said arc chute to cool the same rapidly.

2. In an electric circuit-interrupting device, 35 the combination of an insulating arc chute into which the arc to be interrupted is adapted to be directed having side walls disposed in closely spaced parallel relationship so as to form a narrow arc space therebetween, said walls on 40 the sides facing each other having thereon a plurality of ribs, said ribs being so shaped and disposed and so interleaved with each other as to provide for the arc a continuously lengthening path between said side walls which is zigzag 45 transversely to the normal direction of arc expansion, the transverse spacing between said ribs decreasing in said direction of arc expansion to effect a gradual squeezing of the arc to force it into more intimate contact with said arc chute 50 and means including gas evolving insulating material mounted adjacent the entrance to said arc chute so that when subjected to the heat of said arc gases are evolved which drive the arc into said arc chute to extinguish the same.

3. In an electric circuit-interrupting device, 55 the combination of an insulating arc chute into which the arc to be interrupted is directed having side walls disposed in closely spaced parallel relationship so as to form a narrow arc space therebetween, said walls on the sides facing each other 60 having thereon a plurality of saw-tooth shaped ridges, said ridges being so disposed and so interleaved with each other as to provide for the arc a continuously lengthening path between said side walls which is zigzag transversely to the 65 normal direction of arc expansion, said saw-tooth shaped ridges being progressively thickened in the direction of arc expansion to effect a gradual squeezing of the arc thereby to increase the heat transfer to said arc chute.

4. In an electric circuit interrupter including means between which an electric arc is adapted to be formed, an arc-extinguishing structure comprising a plurality of arc chutes alternately arranged between sections of gas-evolving insulating

material and serially arranged with respect to said arc, magnetic means for forcing said arc into said arc chutes and against said gas-evolving insulating material, said arc chutes each comprising a pair of parallel plates having rib-like projections on the adjacent faces thereof so shaped and disposed and being so interleaved with each other as to provide for said arc a continuously lengthening path between said plates which is zigzag transversely to the normal direction of arc expansion.

5. In an electric circuit interrupter including means between which an electric arc is adapted to be formed, an arc-extinguishing structure comprising a plurality of arc chutes circumferentially arranged and spaced from one another by sections of insulating material, magnetic means for forcing said arc into said arc chutes, a gas-evolving insulating material being disposed adjacent the entrances to said arc chutes so that gas under pressure is produced when said arc acts on said gas-evolving material to aid said magnetic means in forcing said arc into said arc chutes, each of said arc chutes comprising a pair of parallel plates having the adjacent faces thereof serrated, the serrations being so disposed as to be interleaved with each other so as to provide a continuously lengthening path for said arc which is zigzag transversely to the normal direction of arc expansion.

6. In an electric circuit interrupter including means between which an electric arc is adapted to be formed, an arc-extinguishing structure comprising a plurality of arc chutes spaced from one another by sections of insulating material, magnetic means for forcing said arc into said arc chutes, said arc chutes each comprising a pair of parallel plates having the adjacent faces thereof serrated, the serrations being so disposed as to be interleaved with each other so as to provide a continuously lengthening path for said arc which is zigzag transversely to the normal direction of arc expansion, said serrations being progressively thickened in the direction of arc expansion to effect a gradual squeezing of the arc thereby to increase the heat transfer to said arc chute.

7. In an electric circuit-interrupting device, the combination of an insulating arc chute into which the arc to be interrupted is adapted to be directed having side walls disposed in closely spaced relationship so as to form a narrow arc space therebetween, said walls on the sides facing each other being so disposed as to provide for the arc a continuously lengthening path between said side walls, the spacing between said walls progressively decreasing in the direction of arc expansion to effect a gradual squeezing of the arc to force it progressively into more intimate contact with said arc chute and means including gas evolving insulating material mounted adjacent the entrance to said arc chute so that when subjected to the heat of said arc gases are evolved which drive the arc into said arc chute to extinguish the same.

8. In an electric circuit-interrupting device, the

combination of an insulating arc chute into which the arc to be interrupted is directed having side walls disposed in closely spaced relationship so as to form a narrow arc space therebetween, said walls on the sides facing each other being so disposed as to provide for the arc a continuously lengthening path between said side walls, the spacing between said walls progressively decreasing in the direction of arc expansion to effect a gradual squeezing of the arc to force it progressively into more intimate contact with said arc chute, the product of the length and the width of the arc space between said side walls at the exhaust extremity of said chute being of substantially the same order as the product of the length and the width of the arc space at the entrance to said arc chute.

9. In an electric circuit interrupter including means between which an electric arc is adapted to be formed, an arc-extinguishing structure comprising an arc chute arranged between sections of gas-evolving insulating material, and means for moving said arc to the entrance of said arc chute and into active proximity to said gas-evolving insulating material so that gases are evolved therefrom which drive the arc into said arc chute to interrupt the same.

10. In an electric circuit interrupter including means between which an electric arc is adapted to be formed, an arc-extinguishing structure comprising a plurality of arc chutes alternately positioned between sections of gas-evolving insulating material, and means for moving said arc to the entrance of said arc chute and into active proximity to said gas-evolving insulating material so that gases are evolved therefrom which drive the arc into said arc chutes to interrupt the same.

11. In an electric circuit interrupter including means between which an electric arc is adapted to be formed, a circular blow-out means, an arc-extinguishing structure comprising a plurality of arc chutes arranged in an arcuate form about said circular blow-out means which is common to all of said arc chutes, a plurality of sections of gas-evolving insulating material alternately arranged with said arc chutes around said circular blow-out means, means for moving said arc to the entrance of said arc chute and into active proximity to said gas-evolving insulating material so that the gases evolved are exhausted through said chute to drive said arc into said chute for arc-extinguishing purposes.

12. In an electric circuit interrupter including means between which an electric arc is adapted to be formed, an arc extinguishing structure comprising an arc chute constructed chiefly of refractory material but including a minor amount of gas evolving insulating material located in the region of the entrance to said arc chute, and means for moving said arc to the entrance of said arc chute and into active proximity to said gas evolving insulating material so that gases are evolved therefrom to assist in driving said arc into said chute to extinguish the same.
